H. F. WAITE,
FLUOROSCOPIC X-RAY SYSTEM.
APPLICATION FILED NOV. 20, 1920.

Patented Dec. 13, 1921.

INVENTOR

HARRY F. WAITE

BY

O. D. May Edwards

ATTORNEY

UNITED STATES PATENT OFFICE.

HARRY F. WAITE, OF NEW YORK, N. Y.

FLUOROSCOPIC X-RAY SYSTEM.

1,400,833.

Specification of Letters Patent. Patented Dec. 13, 1921.

Application filed November 20, 1920. Serial No. 425,295.

To all whom it may concern:

Be it known that I, HARRY F. WAITE, a citizen of the United States, and a resident of the city of New York, county of Queens, 5 and State of New York, have invented a new and useful Improvement in Fluoroscopic X-Ray Systems, of which the following is a specification.

In systems of this character, it is necessary to have a movable screen which may be placed at any desired level, and back of it and in proper relation thereto, there is an X-ray tube which is shifted by horizontal and vertical movements according to the 10 needs of the operator using the device. In such devices it has heretofore been customary to supply both the cathode and the anode of the tube with electricity brought through wires which are mounted on spring 15 controlled spools which automatically compensate for the position of the tube, which is movable with regard to the transformer, which is fixed. While this wire connection with the cathode is desirable, the other connection with the anode is undesirable because the anode is at the top of the tube and therefore not accessible to a connection with the wire on the spool which is located below the tube and on the transformer and for 20 the additional reason, this anode wire will at times function badly so that it produces a corona effect when the tube is in use and thereby greatly impairs the usefulness of the tube.

The object of my invention is to provide a sure and certain connection between the anode and the transformer which is sure to function properly under all circumstances and provide for all the desired movements 25 of the tube without in any way interfering with the passage of electricity to the anode, and a further object is to overcome the corona effect. Both of these objects are accomplished by my invention, one embodiment 30 of which is hereinafter more particularly set forth.

For a more detailed description of my invention, reference is to be had to the accompanying drawings, forming a part hereof, in which—

Figure 1 is a perspective view, partially broken away, of a vertical fluoroscopic unit embodying my invention.

Fig. 2 is a sectional view showing a detail 55 of construction.

Throughout the various views of the

drawings, similar reference characters designate similar parts.

My improved unit 1 is provided with the conventional fluoroscopic screen 2 mounted 60 in the usual manner by cords 3 which pass over pulleys 4 on the top of a cabinet 5 to a counter-weight, not shown, which is also connected to a cord 6 which runs over a pulley 7 to a vertical, movable frame 8 which 65 carries a horizontal, movable frame 9 which in turn is provided with a bracket 10 that supports the casing 11 of an X-ray tube 12 in the conventional manner.

The bottom of the unit is provided with a 70 transformer 13 which is connected in the conventional manner with any suitable source of electricity through a cable conductor 14 and has a second cable 15 that runs to a regulator 16 and it also carries a 75 cut out switch 17 which is connected in any suitable manner with the transformer 13. This transformer 13 also has a cathode lead 18 which is connected by a cable 19 with the cathode end of the tube 12, in the conventional manner, and another lead 20 which is connected to a rod or tube 21 by a conductor 22 and this rod 21 has its lower end secured in a suitable insulating socket 23 which rests on top of the transformer 13 and 80 is supported in any suitable way and its upper end terminates in a corresponding insulator 24 which is fixed at the top of the cabinet 5. This rod on tube 21 is made of 85 very large diameter as compared with the 90 diameter of a wire such as has been described above, which is generally used for supplying electricity to an X-ray tube and this rod 21 has a smooth, regular external surface which is preferably nickel plated 95 and provided with a laterally extending rod 25 which is provided with a perforated outer end that slides freely on the rod 21 and its inner end slides freely in a tube 26 with a perforated inner end that turns freely on 100 the anode 27 of the tube 12. It is apparent that the telescoping of the parts 25 and 26 and the turning of these parts on the rod 21 and anode 27 respectively, permit ample compensation to be made for all horizontal 105 movements of the frame 9 and the sliding of the part 25 on the rod 21 provides for all vertical movements of the frame 8 so that when the tube is shifted either horizontally or vertically, or both, a proper electrical connection is always made between the anode 110 and the transformer and it is always made

with a large conductor which is large enough to overcome all corona tendencies which are very objectionable as they light up what should be a dark room. They also 5 release ozone.

While I have shown and described one embodiment of my invention, it is obvious that it is not restricted thereto but is broad enough to cover all structures that come 10 within the scope of the annexed claim.

What I claim is:

In a device of the class described, an X-ray tube and means for movably supporting the same, a source of electricity for said

tube, means for connecting the cathode of 15 the tube to the said source of electricity and an adjustable means for connecting the anode of this tube to this source of electricity composed of a fixed rod with a slidably mounted, pivoted and laterally extending means 20 so that when the device is in use the anode and source of electrical supply will always be properly connected by a conductor of large capacity which will overcome or reduce corona effects.

In testimony whereof I have set my hand this 12th day of November, 1920.

HARRY F. WAITE.
